UNITED STATES PATENT OFFICE.

ALEXANDER CARMICHAEL, OF WESTERLY, RHODE ISLAND.

DAMPER-REGULATOR.

SPECIFICATION forming part of Letters Patent No. 717,810, dated January 6, 1903.

Application filed December 21, 1901. Serial No. 86,726. (No model.)

To all whom it may concern:

Be it known that I, ALEXANDER CARMICHAEL, a citizen of the United States, residing at Westerly, in the county of Washington, in the State of Rhode Island, have invented a certain new and useful Improvement in Damper-Regulators, of which the following is a specification.

The invention is an improvement on the damper-regulator set forth in the patent to John E. Spencer, dated September 29, 1885, No. 327,337. I have encountered difficulties in the use of the Spencer regulator as heretofore made which this invention is intended to obviate.

In view of the full description of the Spencer regulator in the patent above referred to it will be sufficient for the present purpose to present a small outline-drawing showing the general arrangement and larger drawings showing the improvement which I have made in important details.

The accompanying drawings form a part of this specification and represent what I consider the best means of carrying out the invention.

Figure 1 is a general side elevation showing the entire apparatus. Fig. 2 is a central vertical section through a portion on a larger scale. It shows a good form of the invention. Fig. 3 is a corresponding section through a smaller portion on a still larger scale. Fig. 4 is on the same scale as Fig. 3 and is a section showing one of the parts detached, with a modification. Fig. 5 is a section of a portion corresponding to Fig. 2, varying therefrom and showing what I esteem the most complete form.

Similar letters of reference indicate corresponding parts in all the figures where they appear.

The Spencer regulator is of the class in which a small double piston-valve is moved axially with each change of pressure of steam in the boiler, and being perfectly balanced has only the slight resistance of friction to oppose its motion. The movement of the damper is effected through strong connections from a relatively large piston inclosed in a corresponding fixed cylinder and subject to pressure of water from an elevated tank or other source of supply furnishing water at

a considerable pressure. The small and easily-moved valve is connected by levers to a diaphragm and so influenced by the pressure of steam that it will rise with each increase of pressure and sink with each decrease below the required standard however nearly shut or widely open the piston may previously stand. There is a hollow piston-rod from each face of the piston, one extending upward and another extending downward, each through a stuffing-box. (Not shown.) The lower hollow rod serves to discharge the water after it has strongly moved the piston and also to communicate the force to operate the damper and to perform an almost equally important function in resisting any irregular movement which a large damper, perhaps imperfectly balanced and subject to the strong flow of the gases in the flue, may attempt to make.

The large piston B is packed on each face with a cup-packing C, covered by a plate D, which is pressed upon the packing by a nut E, the continuation of the passage b through the cup-packing and through the plate being provided by a hole in each in the required position. The upper and lower faces of the piston being alike, a description of the upper alone will suffice for both.

The hole c in the packing C and the hole d in the plate D must coincide with each other and with the passage in the piston. There has always been a liability of the holes to get out of coincidence with each other and with the passage. If with the parts nicely arranged a wrench was applied to further tighten the nut E, the friction of the nut was liable to turn the plate D and sometimes also the cup-packing C, which is, as usual, of yielding material, as leather or soft rubber. Furthermore, if a strong compressive force was exerted through the plate D there was a liability of the yielding material of the cup-packing to gush inward, so as to partially or completely close the hole c. Either of these defects makes the holes partially or completely ineffectual.

I introduce a short length of tube M in the enlarged end b' of the passage b, projecting sufficiently to extend through the packing C and also nearly or quite through the plate D. This short tube insures absolute coincidence

of position, and the interior of the tube being of sufficient diameter the construction permits the free motion of the water upward and downward as required under all conditions.

5 I provide a corresponding shallow hole at another point in the piston, which may be of the same size as the passage *b* or preferably somewhat smaller. *N* is a pin tapped therein. There are corresponding holes made in 10 the packing *C* and in the plate *D*, allowing this pin, like the tube *M*, to extend out nearly but not quite to the outer face of the plate. This pin further aids to hold the parts against turning.

15 The hollow piston-rod *B'*, extending upward, carries on a separately-formed boss *G*, rigidly set thereon, the movable arm *G'*, on which the light lever *H* is fulcrumed. Through the center of this hollow piston-rod *B'* extends a rod *I*, which connects the controlling-valve *J* to the said lever *H*. With any ordinary water the correct action of the regulator necessitates a frequent removal and cleansing of the small double piston-valve *J* and of the 20 interior of the bore *b*, in which it works. As heretofore constructed such cleaning of the valve and adjacent surfaces involved a dismantling of the machine to the extent of removing the thimble *F*, which latter serves the 25 important duties of firmly locking the boss *G* and also of sufficiently closing the annular space in the top of the hollow piston-rod *B'* around the rod *I* to exclude dust and other solid materials. Such removal necessarily 30 liberates the arm *G'*. My improvement avoids 35 the necessity for removing or in any wise disturbing those parts.

I make the valve *J* and the axial bore *b*, in which it plays in the piston *B*, considerably 40 smaller than the interior of the hollow piston-rod *B'*, and I make so large a hole in the center of the thimble *F* as to allow the valve to be inserted and removed through such 45 hole. There is sufficient metal in the thimble to enable it to perform one function of being strongly screwed down to secure the arm *G*. I enable the thimble to perform its other function of sufficiently closing the top of the hollow piston-rod by either making the 50 valve-rod large, so as to practically fill the large hole in the thimble of itself, as shown in Fig. 2, or, as I consider preferable, I keep the valve-rod small and fit thereon a loose sleeve *I'* of the proper size, as shown in Fig. 55 5. In the latter case I make the large hole in the thimble tapering and the sleeve correspondingly tapering, as shown. The device thus equipped serves in all respects in the same manner as with the thick rod, except 60 that the sleeve does not move with the frequently-recurring movements of the rod. On the contrary, the rod moves through the loose-fitting hole in the center of the sleeve, which latter is relatively stationary. The 65 device serves, as with the Spencer construction, until it is desired to remove the valve. Then the valve-rod being liberated from the

lever *H* the valve is simply lifted by the rod, and when raised to a certain extent it lifts the sleeve, and the valve and rod and sleeve 70 are removed together. The reverse movement replaces these parts. In short, I have discovered that by keeping the valve *J* of small diameter and making the rod *I* substantially of large diameter and making a correspondingly large hole in the thimble *F*, I am able to remove the valve by simply drawing the large rod and the attached valve directly upward and to replace it after the cleaning has been effected by a reverse movement. 80 In preparation for effecting this with perfect freedom it is only necessary to pull out the pins *J'* and *G'*, connecting this rod to the lever *H* and to the fulcrum *G*, and to lift the lever *H* out of the way. The thimble *F*, having its large hole, performs the same function as before of serving as means for strongly and rigidly connecting the arm *G* to the hollow piston-rod *B'* and also of making a fairly 85 dust-tight fit around the piston-rod. 90

Modifications may be made without departing from the principle or sacrificing the advantages of the invention. The tube *M* may be tapped into the hole *b'*; but I have in my experiments found it sufficient to simply 95 match the sizes very nicely and drive the tube to the proper depth into the hole by percussion. The tube will perform the function of defending the hole against the displacement or deformation of the packing alone by 100 being of less length, only sufficient to extend through or nearly through the packing.

Instead of tapping or driving the pin *N* in the piston and providing a loose-fitting hole in the plate *D* to receive it I can tap or otherwise firmly set the pin into the plate *D* and allow it to extend through the packing in the opposite direction and engage loosely in a hole in the piston, as indicated in Fig. 4. This pin, set in either way, may serve alone 105 without the tube *M*; but in such case the important function of protecting the other hole *c* against being closed by the intrusion of the yielding packing into the space, which should be kept clear, will be sacrificed. On the other 110 hand, the tube *M* may serve alone if allowed to extend sufficiently to take a reliable hold of the plate, and the pin *N* may be dispensed with. 115

I claim as my invention—

1. In a damper-regulator, the combination of a cylinder, a piston provided with a longitudinal passage and with two passages leading from separate points in said longitudinal passage to the respective ends of the piston, 125 a hollow piston-rod, a valve operated by an inclosed rod for governing said passages, cup-packings of yielding material for the ends of the piston, and plates for securing such packings in position, and a short tube extending through each packing stiffly set in one of the parts and engaged loosely in the other so as to apply the rigidity of its mounting to perform the double function of preventing any 130

relative turning motions and keeping open the passage through the soft packing, all substantially as herein specified.

2. In a damper-regulator having a cylinder and a piston with a hollow piston-rod, and a rigidly-attached arm G G' carrying a lever H, an internal valve operated through such piston-rod, and a liberally-apertured thimble F on such rod serving both for securing the parts and to close the space around the valve-rod, in combination with a piston-valve of small diameter serving to control the larger piston, adapted to be inserted and removed through such thimble, and a sleeve I' fitted loosely on the valve-rod and supported in such thimble free to be raised in withdrawing the valve, all substantially as herein specified.

3. In a damper-regulator having a cylinder and a piston with a hollow piston-rod, and a rigidly-attached arm G G' carrying a lever H

an internal valve operated through such rod, and a liberally-apertured thimble on such rod 20 serving both for securing the parts and to close the space around the valve-rod, in combination with a piston-valve of small diameter serving to control the larger piston adapted to be inserted and removed through such 25 thimble, and a sleeve I' fitted loosely on the valve-rod and supported in such thimble free to be raised in withdrawing the valve, all substantially as herein specified.

In testimony that I claim the invention 30 above set forth I affix my signature in presence of two witnesses.

ALEXANDER CARMICHAEL.
